Primary Examiner—Catherine Tuttle

(57) **CLAIM**

The ornamental design for a ball, as shown and described.

DESCRIPTION

FIG. 1 is a top front perspective view of the ball showing my new design;

FIG. 2 is a top plan view of FIG. 1;

FIG. 3 is a right front elevational view of FIGS. 1 and 2, the left front and rear elevational views being identical thereto; and,

FIG. 4 is a bottom view rotated so that the upper vertical projection corresponds to one of the lower projections in FIG. 3.
